UNITED STATES PATENT OFFICE.

STEPHEN M. WELLS, JR., OF BRISTOL, CONNECTICUT, ASSIGNOR TO THE GREYSTONE MANUFACTURING COMPANY, OF GREYSTONE, CONNECTICUT, A CORPORATION OF CONNECTICUT.

HALTER-CHAIN.

SPECIFICATION forming part of Letters Patent No. 690,801, dated January 7, 1902.

Application filed May 1, 1901. Serial No. 58,355. (No model.)

To all whom it may concern:

Be it known that I, STEPHEN M. WELLS, Jr., a citizen of the United States, residing at Bristol, in the county of Hartford and State 5 of Connecticut, have invented certain new and useful Improvements in Halter-Chains; and I do hereby declare the following to be a full, clear, and exact description of the invention, such as will enable others skilled in 10 the art to which it appertains to make and use the same.

The present invention relates to chains for leading and tying or hitching animals, and has for its object to produce an improved device 15 whereby the usual and ordinary chain carrying at one end a T bar or toggle may be quickly formed into a loop and secured around a hitching-post or stanchion. Such chains are usually formed of sheet-metal 20 links, and prior to the present invention a plate having substantially a keyhole-slot has been provided designed to be passed over the chain and to receive the T-bar, thus forming a loop in the chain. This device has been 25 found to be objectionable, for the reason that there was no positive means for preventing the accidental drawing of the chain through the keyhole-opening, and it was found that the movements of the animal when secured 30 by the chain caused such accidental drawing of the chain through the plate and the consequent loosening or tightening of the loop.

In the present invention the opening in the plate is provided with means for positively 35 engaging the chain-link, and when the T-bar is engaged by said plate the chain is positively prevented from being drawn through the same.

The present invention consists of the devices 40 and combinations of devices which will be hereinafter described, and pointed out in the claims.

The present invention is illustrated in the accompanying drawings, in which—

45 Figure 1 shows a portion of the ordinary and well-known chain, showing the operation of my improved loop-plate. Fig. 2 shows the loop-plate removed from the chain. Fig. 3 shows the loop-plate and a portion of the

chain engaged by the loop-plate prior to the 50 connection of the T-bar therewith. Fig. 4 is a similar view illustrating the position of the link which carries the T-bar when connected with the plate to form a loop in the chain.

Similar reference-letters will be employed 55 throughout the specification and drawings to designate corresponding parts.

In the drawings, *a* shows a chain composed of the usual sheet-metal links, such chain being well-known and need not be particularly described. At one end the chain *a* carries a T-bar *b*, which is loosely connected to the eye of the end link of the chain.

It is desirable at times to form a loop *c* in the chain *a*, to be placed around a hitching-post or stanchion, and for this purpose I have provided the loop-plate *d*. As shown in the drawings, the loop-plate is substantially rectangular in shape and formed of any suitable sheet metal, preferably steel, and it is provided with an opening *e*, said opening being substantially circular at its upper end and having the downwardly-diverging slots *f* communicating with the circular part of the opening, thus providing the upwardly-extending 65 post *g*, which terminates substantially at the periphery of the circular portion of the opening *e*. The post *g* is designed to engage any link in the chain either in the elongated slot 70 of the link or in the eye *h* at a suitable distance from the T-bar *b* to form a loop *c* of the desired size.

After the post *g* has engaged a link the T-bar *b* is passed through the circular opening *e* and drawn back into the position shown in 85 Fig. 1, whereupon the eye *h* of the link which carries said T-bar will assume the position shown in Fig. 4, thus effectually preventing the disengagement of the loop-plate *d* from the link of the chain with which the post *g* 90 has been connected.

An important advantage possessed by my loop-plate over those of the prior art is that the chain is positively held from accidental slipping through the plate, and, again, the 95 loop-plate may be connected with either the eye or the elongated slot of a link, and thus the formation of the loop in the chain may

be quickly accomplished without the necessity of carefully adjusting the chain-link in the loop-plate, which is necessary with those devices of the prior art which are adapted only to engage a certain portion of the link.

Having described my invention, I claim as new and desire to protect by Letters Patent of the United States—

1. The combination with a chain, provided with a **T**-bar, of a loop-plate carried by said chain provided with an opening designed to permit the free passage of the chain through the plate, and means in said opening for engaging one of the chain-links, substantially as described.

2. The combination with a chain, provided

with a **T**-bar, of a loop-plate carried by said chain provided with an opening for the free passage of the chain, and a post to engage one of the chain-links, substantially as described.

3. A loop-plate for chains provided with a substantially keyhole-shaped opening, and having a post extending from the base of said opening toward the circular part, substantially as described.

In testimony whereof I affix my signature in presence of two witnesses.

STEPHEN M. WELLS, JR.
